UNITED STATES PATENT OFFICE.

MAURICE L. TOWNSEND, OF CHARLOTTE, NORTH CAROLINA.

INHALER.

1,262,874.

Specification of Letters Patent. Patented Apr. 16, 1918.

Application filed April 26, 1917. Serial No. 164,686.

To all whom it may concern:

Be it known that I, MAURICE L. TOWNSEND, a citizen of the United States, residing at Charlotte, in the county of Mecklenburg and State of North Carolina, have invented 5 certain new and useful Improvements in Inhalers; and I do declare the following to be a full, clear, and exact description of the invention, such as will enable others skilled 10 in the art to which it appertains to make and use the same.

My invention relates to that class of devices intended principally for administering anesthetics such as ether and chloroform, although it will be understood that 15 the device may be used for all other purposes necessitating inhalation of fumes.

I am aware that numerous devices have heretofore been employed for the purposes 20 above defined, but my invention aims primarily to provide a novel type of inhaler in which the receptacle for the anesthetic or the like is carried within a mask, when the device is not in use, said mask serving to 25 confine the fumes around the patient's nose and mouth.

A further object is to provide a detachable connection between the mask and receptacle operable upon relative turning thereof, and 30 to provide a valve operated by additional turning of said mask and receptacle for controlling the strength of the fumes drawn from the latter by breathing of the patient.

In carrying out the last named object, a 35 number of air passages having partitions therein are provided, said partitions being covered with absorbent material to be saturated with the liquid from which fumes are to be inhaled, a further object of the invention being to provide novel means for holding the coverings of said partitions in place and for spacing said partitions apart.

With the foregoing general objects in view, the invention resides in the novel features of construction and unique combinations of parts to be hereinafter fully described and claimed, the descriptive matter being supplemented by the accompanying drawings which constitute a part of this 50 application and in which:

Figures 1 and 2 are side elevations of the improved inhaler;

Fig. 3 is a sectional view thereof on the plane of the line 3—3 of Fig. 2;

55 Fig. 4 is a transverse section on the plane indicated by the line 4—4 of Fig. 3;

Fig. 5 is a perspective view of receptacle for the anesthetic or the like;

Fig. 6 is an end elevation of the mask;

Fig. 7 is a perspective view of the two 60 annular frames and the valve between said frames for controlling the currents of air between the passages thereof; and

Fig. 8 is a side elevation, partly in section, showing the receptacle nested in the mask 65 for carrying from place to place.

In the drawings above briefly described, the numeral 1 has reference to a preferably cylindrical receptacle closed at both of its ends, whereas the numeral 2 designates a 70 mask preferably constructed of metal and shaped to fit over the patient's nose and mouth, said mask being of cylindrical outline and of a size to receive therein the receptacle 1 when the device is not in use, 75 whereby the entire inhaler may be carried in a physician's satchel or in any other compact space. One end of the receptacle 1 is provided with a hollow plug 3 threaded externally for reception in a socket 4 carried 80 by the closed end of the mask 2, the wall of said socket having perforations 5 for admitting fresh air into the same, which air is adapted to pass through the hollow plug 3 into the receptacle 1. In the latter, this 85 air is subjected to the anesthetic or other substance from which the fumes are to be inhaled and is then drawn into the mask 2 by the respiration of the patient, said mask having a suitable check valve 6 which 90 opens outwardly to permit the free expulsion of the patient's breath.

By reference to the drawings, it will be observed that the plug 3 is positioned at the center of the receptacle 1. This is a 95 highly important feature, since said plug is thus receivable in an internally threaded socket 7 at the closed end of the mask 2. The mask and receptacle may thus be rigidly connected when the latter is inserted in the 100 former.

By inserting the plug 3 in the socket 4 and turning the receptacle and mask relatively, the two will be rigidly connected, and additional turning of these parts to a 105 number of predetermined positions, will vary the strength of the fumes entering the mask, this result being obtained by the construction now to be described.

Two frames 8 and 9 are positioned in the 110 receptacle 1 in parallel planes, each of said frames consisting of a ring 10 at its periph-

ery, a split ring 11 at its center, a radial partition 12 joining one end of the split ring with the ring 10, and a radial arm 13 connecting the other end of said split ring with the other ring. By this construction, each of the frames 8 and 9 is formed with an arcuately extending blind passage 14, the closed ends of these passages being formed by the partitions 12. Arcuate partitions 15 are disposed in the passages 14 and said partitions as well as the other parts of the frames 8 and 9 are provided with coverings 16 of absorbent material. To hold the coverings of the partitions in place and at the same time to space said partitions from each other and from the rings 10 and 11, coils 17 extend along the sides and around the ends of said partitions as illustrated in Figs. 3 and 4.

The passage 14 of the inner frame 8 is in direct communication, at its open end, with a tubular air inlet 18 extending inwardly from the hollow plug 3, the latter being preferably formed by the outer end of said inlet. The open end of the passage 14 of the outer frame 9, communicates with the interior of a hollow valve stem 19 by way of perforations 20 formed in said stem. Stem 19 is positioned at the axis of the receptacle 1 and has its outer end disposed in the hollow plug 3 for telescopic engagement with a tube section 21 secured centrally within the socket 4 and communicating with the interior of the mask. Suitable means, such as a groove 22 and rib 23, are provided for so connecting the tube section 21 and the tubular stem 19, as to cause the latter to be turned from the former to set the valve 24 as required.

The valve 24 is in the form of a disk interposed between the two frames 8 and 9 and having perforations 25 for placing different points of the two passages 14 in communication. It will thus be obvious that the length of contact of the air current with the saturated material in the passages may be readily controlled. When the perforations 25 are in registration with the gaps 26 between the partitions 12 and the arms 13, the air taken into the device, will pass from the gap 26 of frame 8 through the perforations 25 and into the corresponding gap of frame 9. From the latter it will enter the tubular valve stem 19 through the perforations 20 and by way of said stem and tube section 21, will be drawn into the mask 2 to be inhaled by the patient. In taking this course, the air comes in contact with practically none of the saturated material and is thus impregnated only to a slight extent with fumes therefrom. By turning the mask and receptacle relatively, however, the valve 24 is set so that the perforations 25 may establish communication between different points of the two passages 14. By so doing, the air currents may be

made to travel throughout any fractional part of one passage before they are expelled into the other, and in the latter the air must travel still farther before it is discharged into the valve stem 19. Obviously, the strength of the fumes inhaled by the patient will increase or decrease according to the length of time which the air currents impinge upon the saturated material in the receptacle 1, and thus the strength of said fumes may be accurately controlled by simply turning the mask and receptacle in respect to each other. Said receptacle is provided with suitable indicating characters such as numbers for coaction with the valve 6 in determining the several positions of the valve 24. Other suitable indicating means, however, could well be employed.

From the foregoing, taken in connection with the accompanying drawings, the construction, manner of operation and advantages of my improved inhaling device will be readily understood and it will be obvious that although the invention is simple and inexpensive, it will be highly efficient and durable. Probably the best results are obtained by the specific construction shown and described, and in fact I have successfully used the device manufactured in this way. This construction, therefore, constitutes the preferred form of the inhaler. I wish it understood, however, that within the scope of the invention as claimed, numerous minor changes may be made without sacrificing the principal advantages.

I claim:

1. An inhaler comprising a receptacle having at one end a coupling member, said receptacle being adapted to contain a substance from which fumes are to be inhaled, a mask of a size to receive said receptacle therein when the device is not in use, said mask having a substantially closed end, a coupling member carried by said end of the mask for coaction with said first named coupling member to operatively connect said mask and receptacle, and a third coupling member on the interior of said substantially closed end of the mask for coöperation with said first named coupling member to secure the mask and receptacle together when the latter is positioned in the former.

2. An inhaler comprising a receptacle to contain a substance from which fumes are to be inhaled, a mask for application to the patient's face, a coupling connecting said mask and receptacle for relative movement, and means in said receptacle for controlling the strength of the fumes discharged therefrom, said fume controlling means having an operating member positioned in said coupling and operatively connected with said mask for actuating said means upon relative movement of said mask and receptacle.

3. An inhaler comprising a receptacle to contain the substance from which fumes are to be inhaled, a mask for application to the patient's face, said mask being shaped to receive said receptacle therein when not in use, plug and socket members for operatively connecting the mask and receptacle, and means coacting with one of said members for connecting said mask and receptacle when the latter is inserted in the former.

4. An inhaler comprising a receptacle to contain the substance from which fumes are to be inhaled, a mask for application to the patient's face, means operable by relative movement of the mask and receptacle for connecting the two, and means in said receptacle operated by such relative movement of said mask and receptacle for controlling the strength of the fumes entering the former.

5. An inhaler comprising a receptacle to contain the substance from which fumes are to be inhaled, a mask for application to the patient's face, a valve for controlling the strength of the fumes drawn from the receptacle into the mask, said valve having a hollow operating stem acting as the fume outlet from said receptacle, and means carried by the mask and coöperating with said stem to cause relative movement of said receptacle and mask to operate said valve.

6. An inhaler comprising a receptacle to contain the substance from which fumes are to be inhaled, a mask for application to the patient's face, a rotatable valve for controlling the strength of the fumes drawn from said receptacle into the mask, said valve having a hollow operating stem acting as the fume outlet from said receptacle, and means carried by the mask and coöperating with said stem to cause relative turning of the receptacle and mask to operate said valve.

45 7. An inhaler comprising a receptacle to contain the substance from which fumes are to be inhaled, a mask for application to the patient's face, a plug and socket connection between said mask and receptacle and for admitting fresh air into the latter, a rotatable valve for controlling the strength of the fumes drawn from the receptacle, said valve having a hollow operating stem acting as the outlet from said receptacle, said

connection, and means coacting with said stem for turning the same upon relative rotation of the mask and receptacle.

8. An inhaler comprising a receptacle to contain the substance from which fumes are to be inhaled, a mask for application to the patient's face, a plug and socket connection between said mask and receptacle and for admitting fresh air into the latter, a rotatable valve for controlling the strength of the fumes drawn from the receptacle, said valve having a hollow operating stem acting as the outlet from said receptacle, said stem having its outer end positioned in said connection, a short tube section extending into said connection from the mask and telescoping with said stem, and means for preventing relative rotation of said tube section and stem, whereby relative rotation of the mask and receptacle will operate the valve.

9. An inhaler comprising a receptacle provided with a pair of air passages having means for impregnating the air with fumes, one of said passages being open to the fresh air and the other communicating with an air outlet from the receptacle, and means for placing different points of the two passages in communication.

10. An inhaler comprising a receptacle provided with a pair of air passages having means for impregnating the air with fumes, said passages extending arcuately and being located in parallel planes with their adjacent sides open, one passage being open to the fresh air and the other communicating with an air outlet from the receptacle, and a rotary disk valve between said passages for placing different points of the two in communication, said valve closing said open sides of the passages with the exception of a restricted area.

11. An inhaler having an air passage, a partition in said passage having a covering of absorbent material to be saturated with the liquid from which fumes are to be inhaled, and spacing coils extending along the sides of said partition.

In testimony whereof I have hereunto set my hand in the presence of two subscribing witnesses.
